UNITED STATES PATENT OFFICE

129,480

DESIGN FOR A TEXTILE FABRIC

Harry Horowitz, Elizabeth, N. J.

Application December 27, 1940, Serial No. 97,646

Term of patent 3½ years

To all whom it may concern:

Be it known that I, Harry Horowitz, a citizen of the United States and residing at Elizabeth, in the county of Union and State of New Jersey, have invented a new, original, and ornamental Design for Textile Fabric, of which the following is a specification, reference being had to the accompanying drawing, forming part thereof, and in which the figure of the drawing is a plan view of a textile fabric showing my design.

I claim:

The ornamental design for a textile fabric, substantially as shown.

HARRY HOROWITZ.
